SOAP DISH OR SIMILAR ARTICLE

Robert A. O'Neil, Pittsburgh, Pa., assignor to Fesco, Inc.,
New York, N.Y., a corporation of Delaware

Filed July 8, 1965, Ser. No. 86,077

Term of patent 14 years

(Cl. D4—3)

Fig. 1.

Fig. 2.

Fig. 3.

FIGURE 1 is a top plan view of a soap dish or similar article showing my new design;

I claim:

The ornamental design for a soap dish or similar article, as shown.
